PLATE

Paul Schneeloch, New York, N. Y.

Application March 2, 1953, Serial No. 23,836

Term of patent 14 years

(Cl. D36—2)

To all whom it may concern:

Be it known that I, Paul Schneeloch, a citizen of the United States, residing at New York, in the county of New York and State of New York, have invented a new, original, and ornamental Design for a Plate, of which the following is a specification, reference being had to the accompanying drawing, forming part thereof.

In the drawing:

Fig. 1 is a top plan view of a plate, showing my new design;

Fig. 2 is a bottom view of the same; and

Fig. 3 is a vertical sectional view taken on line 3—3 of Fig. 1.

I claim:

The ornamental design for a plate, as shown.
PAUL SCHNEELOCH.
